To all whom it may concern:

Be it known that I, Peter Altman, a citizen of the United States of America, residing at Detroit, in the county of Wayne and State of Michigan, have invented a new, original, and ornamental Design for Airplanes, of which the following is a specification, reference being had to the accompanying drawings, forming part thereof.

The characteristic features of my design reside in the portions shown by means of full lines in the drawings.

I claim:
